UNITED STATES PATENT OFFICE.

SIGMUND STERNAU, OF NEW YORK, N. Y.

DESIGN FOR A TILE-STAND.

SPECIFICATION forming part of Design No. 23,771, dated November 6, 1894.

Application filed October 6, 1894. Serial No. 525,180. Term of patent 3½ years.

To all whom it may concern:

Be it known that I, SIGMUND STERNAU, a citizen of the United States, residing in New

York, county of New York, and State of New

5 York, have invented and produced a new and original Design for Tile-Stands, of which the following is a specification, reference being had to the accompanying drawing, which shows the tile-stand in perspective.

10 The leading or characteristic feature of my design is the fanciful ornamented body of the design, having the waved outline as shown, and supported on the outwardly extending ornamented legs or supports.

A represents the sides of the stands, having 15 the waved or curved outline, and the ornamental surface as shown.

B represents the outwardly extending legs, also ornamented as shown.

What I claim is—

20 The design for a tile stand as hereinabove shown and described.

SIGMUND STERNAU.
